CLAIM

The ornamental design for a pet backpack, as shown and described.

DESCRIPTION

FIG. 1 is a perspective view of the pet backpack showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the pet backpack when the top portion is detached from the bottom portion;

FIG. 10 is an exploded perspective view of the pet backpack when both the top portion and bottom portion are open; and,

FIG. 11 is a perspective view of the bottom portion of the pet backpack in a closed configuration.
